UNITED STATES PATENT OFFICE.

EDWIN H. ARMSTRONG, OF YONKERS, NEW YORK, ASSIGNOR, BY MESNE ASSIGNMENTS, TO WESTINGHOUSE ELECTRIC & MANUFACTURING COMPANY, A CORPORATION OF PENNSYLVANIA.

WAVE-SIGNALING SYSTEM.

Application filed June 8, 1922. Serial No. 566,683.

To all whom it may concern:

Be it known that I, EDWIN H. ARMSTRONG, residing at 1032 Warburton Avenue, Yonkers, in the county of Westchester, State of New York, have invented certain new and useful Improvements in Wave-Signaling Systems; and I do hereby declare the following to be a full, clear, and exact description of the invention, such as will enable others skilled in the art to which it appertains to make and use the same.

This invention relates to an electric regenerative system for amplifying varying electric currents, particularly radio or other high frequency signaling currents, wherein the varying potential of the current to be amplified is impressed on the system and the relation between the amount of regeneration and the degree of damping of the system is periodically varied to produce transient free oscillations proportional to the amplitude of the impressed potential and wherein the resulting free oscillations and the system are continuously maintained in this transient ordinarily unstable state to obtain super-regenerative amplification or action as described in my Patent 1,424,065 granted July 25, 1922, on a co-pending application, Serial No. 480,563 filed June 27, 1921.

The invention has for its object the provision of a method of and apparatus for obtaining increased amplification with super-regenerative systems, particularly of the type in which the amount of regeneration, that is, the regenerative energy supplied to the system (the so-called negative resistance) is varied with respect to the degree of damping, that is, the rate of dissipation of the energy of the system.

It has been discovered in the course of operation of super-regenerative systems in which the amount of regeneration is varied with respect to the degree of damping of the system, particularly when employed for the amplification and reception of radio telephone signals, that it is necessary to add positive resistance to the tuning circuits of the system in order to preserve the quality of the received speech. The addition of positive resistance to the circuit, however, is accompanied by a loss in intensity. To the end of overcoming this difficulty and for the purpose of introducing the necessary resistance or damping in the tuned circuit in

such manner that a loss in signal strength does not occur, an arrangement is provided wherein a large number of turns of fine wire of high resistance is coupled to the tuned circuit, the inductance of the tuned circuit serving as a primary of the transformer and the large number of turns of fine wire serving as a secondary thereof. When this circuit arrangement is connected to the grid of the vacuum valve of the regenerative system it acts as a step-up transformer. By coupling such a winding to the proper degree with the tuned circuit, the necessary amount of resistance is introduced in that circuit by the withdrawal of energy from it into the secondary winding. Instead, however, of the energy being wasted in a dead resistance, the energy withdrawn from the circuit is used to create an increased difference of potential across the secondary of the transformer which is then applied to the grid of the vacuum tube or valve.

The particular form of circuit arrangement illustrated in the drawing is the preferred embodiment of the invention. It possesses marked advantages in that it successfully introduces the necessary damping in the tuned circuit of the system in such manner that a loss in signal strength does not occur.

Referring now to the drawing which illustrates the general arrangement of the system; the source 1 of the incoming signal or the varying current to be amplified is associated with the circuit 2, 3 which is tuned to the frequency of the incoming signal or current to be amplified. A high resistance coil 4 is coupled to the tuned circuit and is connected to the grid 5 of the vacuum valve 6. The feed-back coupling 7 in the plate circuit of the valve 6 is associated with the resistance coil 4 and the tuned circuit 2, 3, and serves to control the amount of regeneration of the system. The second vacuum valve 8 connected in the plate circuit of the valve 6 is employed to supply the auxiliary frequency to the regenerative system for the purpose of periodically varying the relation between the amount of regeneration and the damping of the system, in this case serving to vary the amount of regeneration with respect to the damping of the system. The oscillating system furnishing the auxiliary frequency in

cluding the valve 8 is connected to a source of alternating current 9 or other source of electrical oscillations and the plate circuit of the valve 8 includes a second tuned circuit 5 10, 11 adjusted to the frequency of the auxiliary frequency current. The telephones 12 and bypass condenser 13 are also included in the plate circuit of the valve 6 and serve to indicate the received signals. Of course, other equivalent indicating devices 10 may be employed instead of the telephone receivers 12.

The operation of the system is simple and follows generally the mode of operation of 15 super-regenerative systems as described in the aforementioned patent. It will be understood, however, that the function of the coil 4 consisting of many turns of fine resistance wire is to withdraw energy from 20 the tuned circuit 2, 3 and simultaneously serve as the secondary of a step-up transformer whereby an increase of potential is created across the coil which is then applied to the grid 5 of the vacuum valve 6. 25 In this way the necessary damping is introduced into the tuned circuit 2, 3 but in such manner that a loss in signal strength does not occur when the system is amplifying and receiving signals.

30 In the normal operation of the system, the grid 5 does not become positive. Current, therefore, does not flow between the grid and the filament. The grid, however, 35 does change its potential. Moreover, the grid possesses a certain capacity. In order to change its potential, therefore, a charge must flow to or from the grid. There must, therefore, be a current in the connection leading to the grid. This connection 40 includes the coil 4. This coil is made of sufficiently high resistance so that, in spite of the very small size of the current just mentioned, the losses in the coil 4 shall be sufficient to effect the magnitude of the damping. 45

It is to be understood that the present invention is adapted to receive radio sig-

nals, including radio telephone signals, when associated with an antenna, loop or other energy collecting device and to receive wired wireless signals (so-called wire carrier current transmission) when associated with the conductors of such signals. It should also be understood that modifications may be made in the specific circuit connections above described without departing from the spirit and scope of the invention. 50 55

I claim:

1. The method of obtaining increased amplification of signals with super-regenerative systems provided with a tuned circuit and having a certain degree of damping, wherein the relation between the amount of regeneration and the degree of damping is periodically varied, which comprises inductively increasing the energy abstracted from said tuned circuit, and effecting by said additional abstracted energy a corresponding increase of response of the system to signals, whereby the additional abstraction of energy from said tuned circuit is without corresponding loss in signalling strength. 60 65 70

2. An electric regenerative system adapted to produce super-regenerative action 75 comprising a feed-back circuit including a vacuum valve having grid, filament and plate elements connected to their respective circuits, a circuit connected to the filament of said valve which includes an inductance 80 a second circuit connected to the grid of said valve which includes a coil having a high resistance said inductance adapted to serve as the primary and the coil of high resistance as the secondary of a transformer 85 supplying an increased potential to the grid while effectively introducing resistance or damping in said first or primary circuit whereby the necessary damping of the system is obtained substantially without loss 90 in signal strength. 95

In testimony whereof I affix my signature.

EDWIN H. ARMSTRONG.
